UNITED STATES PATENT OFFICE

167,008

MOCCASIN

Virginia G. Spilman, Albuquerque, N. Mex.

Application March 27, 1952, Serial No. 19,068

Term of patent 14 years

(Cl. D7—7)

To all whom it may concern:

Be it known that I, Virginia G. Spilman, a citizen of the United States, residing at Albuquerque, in the county of Bernalillo, and State of New Mexico, have invented a new, original, and ornamental Design for a Moccasin, of which the following is a specification, reference being had to the accompanying drawing, forming a part thereof.

Fig. 1 is a top plan view of a moccasin, showing my new design.

Fig. 2 is a side elevational view thereof.

Fig. 3 is a side elevational view of a moccasin with the cuff thereof upturned into an ankle covering position; and

Fig. 4 is a top plan view of the moccasin as illustrated in Fig. 3.

I claim:

The ornamental design for a moccasin, as shown.

VIRGINIA G. SPILMAN.
